UNITED STATES PATENT OFFICE

ARCHIBALD L. WALLACE, OF BROOKLYN, NEW YORK

MACHINE FOR INTERNALLY THREADING SLEEVES

Application filed January 25, 1929. Serial No. 334,833.

This invention relates to a machine for internally threading sleeves or like tubular members.

An object of the invention is to provide a machine for this purpose wherewith sleeves may be quickly threaded one after the other in rapid succession.

A further and more detailed object is to provide a machine having one part into which unthreaded sleeves may be placed, and having another part for feeding the sleeves in rapid succession to a threading device also comprised in the machine.

A further detailed object is to provide efficient means to care for the delivery of threaded sleeves from the machine.

A further detailed object is to provide means to prevent overheating of the threading device.

20 A further object is to provide improved means by which to remove shavings and chips produced by the cutter.

A further detailed object is to provide simple and efficient means whereby the machine 25 is rendered capable of operating upon sleeves of different sizes.

A further detail object is to provide an improved delivery and washing device for the completed sleeves.

30 Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claims.

In the accompanying drawings which are 40 to be taken as a part of this specification, and in which I have shown merely a preferred form of embodiment of the invention:—

Fig. 1 is a side elevational view, partly in section, of a machine constructed in accordance with this invention.

Fig. 2 is an enlarged vertical sectional view through a portion of the machine as seen in Fig. 1.

Fig. 3 is a vertical sectional view taken 50 upon the plane of line III—III of Fig. 2.

Fig. 4 is a similar sectional view taken upon the plane of line IV—IV of Fig. 2.

Fig. 5 is a detail sectional view of a part of the delivery device embodied in the machine, and

55 Fig. 6 is a horizontal sectional view taken upon the plane of line VI—VI of Fig. 5, and

Fig. 7 is a fragmentary detail view illustrating structural features of the sleeve carrying shell employed.

60 Referring now to the exemplary structure illustrated in the drawings for describing said structure in detail, the reference character L indicates a main platform or bed. This is shown as consisting of a pair of channel irons as 1 and 2 spaced apart and connected together by a suitable cover plate 3. Legs as 4—4 are shown for supporting this bed elevated above the floor 5, and in the space beneath the bed, resting preferably 65 upon the floor 5, is conveniently placed a motor G, a tank H and a wash tank A.

70 Upon the upper surface of the bed L is carried a pair of standards as 6 and 7 for rotatably supporting between them a tubular shell 8 extending longitudinally substantially parallel with the upper surface of the bed but spaced above said surface.

The standard 6 has an opening 9 through which the shell extends, said opening being 80 provided with a ball-race 10 within which engage balls 11 which also engage a co-operative ball-race 12 carried by the shell 8.

85 The standard 7 is cylindrical at its upper end in continuation of the shell 8 and provides a bearing as 13 within which the adjacent end of the shell is rotatable. A gland member as 14 is arranged as a part of this bearing adjustable to compress a gasket as 15 against the outer surface of the shell to 90 provide an oil tight bearing for a reason which will presently be referred to. This standard has an opening as 16 at its upper side through which unthreaded sleeves as 17—17 may move downwardly from a magazine 18 which is conveniently attached at this point. At the lower end of the opening 16, and mounted to reciprocate in the cylindrical portion 19 of the standard aligned with the shell 8 is a plunger 20 operable to 95 100

move the sleeves successively along the length of the shell one with each forward movement of the plunger. This plunger is likewise provided with a gland as 21 operable upon a packing 22 to provide an oil tight joint between itself and the wall of the cylinder 19.

At a suitable point between the standards 6 and 7 the shell 8 carries a sprocket wheel 23. This is engaged by a chain 24 extending from the motor G, the shell being thus connected to be rotated by the motor.

The mechanism for operating the plunger 20 consists of a shaft 25 extending transversely beneath the shell, see Fig. 3, at a location preferably between the standards 6 and 7. A sleeve 26 is mounted to rotate freely upon this shaft and said sleeve and shaft are free to move longitudinally with respect to each other. A worm gear 28 is fixed to the sleeve, as by key 27, and has constant engagement with a worm pinion 29 fixed to the shell 8 so that rotation of said shell will serve to drive the sleeve 26.

Suitable bearings as 30 and 31 are mounted upon the bed L and engage the sleeve for rotatably supporting said sleeve, and beyond said bearings the sleeve is enlarged to provide a pair of oppositely facing friction surfaces as 32 and 33.

Mounted upon the shaft 25, beyond opposite ends of the sleeve is a pair of discs as 34 and 35 respectively, the disc 34 providing a friction surface 36 opposing the friction surface 32, and the disc 35 providing a friction surface 37 opposing the surface 33. These discs are provided with feathers as 38 by which they are connected to rotate with the shaft but being left to move freely longitudinally of the shaft.

Rigidly connected with the discs 34 and 35 are a pair of eccentric cams 39 and 40 respectively which operate within yokes 41 and 42. These yokes are pivotally mounted by their lower ends upon the members 1 and 2 of the bed L as by means of pivot pins 43 and 44, and to their upper ends are pivotally attached a pair of connector rods 45 and 46, said rods in turn having their free ends pivotally connected as at 47 with the outer end of the plunger 20.

A head as 48 is provided at one end of the shaft 25 engaging the outer surface of the eccentric 39, and an adjustable clamp member is provided at the opposite end engaging the eccentric 40, these parts being intended to force the surfaces 36-37 toward the surfaces 32-33 as will be readily understood. Simple clamp nuts as 49-50 may be connected with a threaded extension as 51 of the shaft 25 as indicated to constitute the required adjustable means for this purpose, and suitable friction members as 52 and 53 may be arranged between the surfaces 32-36 and 33-37 so that a desirable smooth clutch-

ing effect is provided by the frictional grip of the mentioned surfaces against the members 52-53.

Adjacent the end of the shell 8 opposite the plunger 20 is arranged a stationary threading device or cutter as 54 and the purpose of the plunger is to force the sleeves one against the other along the interior of the shell from the magazine 18 and against and onto the cutter.

Since it is desirable that the plunger pressure shall continue after the threading operation has begun and until the cutter has taken a good hold upon the sleeve, and since the speed of travel of the sleeve when it has once been gripped by the cutter is positively determined by the pitch of the cutter threads, it is desirable that the plunger shall not be positively driven but shall be capable of stopping or of slowing up whenever it encounters abnormal opposition.

The clutch mechanism above described for controlling the plunger is designed for accomplishing this result. The ratio of the worm gear and pinion 28 and 29 is such that the normal speed of movement imparted to the plunger is relatively greater than the speed of movement of a sleeve over the cutter 54. The gripping power of the clutch is sufficient to force a sleeve onto the cutter but is yet sufficiently weak to provide for slippage between the clutch faces as may be required thereafter until the eccentric cams 39 and 40 pass centre and begin to move the plunger in the opposite direction.

The thread cutter 54 projects axially into the adjacent end of the shell 8, and it will be understood that the sleeves are rotated over said cutter. Rotary movement may be imparted to the sleeves in any appropriate manner but is preferably imparted directly from the shell 8 by interengaging formations provided upon the sleeves and said shell. A simple expedient to this end consists in forming the sleeves with a plurality of longitudinal ribs as 55 and of forming that portion of the shell 8 which surrounds the cutter with co-operative ribs as 56, said ribs interengaging together so that the sleeves are thereby forced to rotate with the shell while passing the cutter, but being of course free to move longitudinally along the shell.

A plurality of spring fingers as 57-57 are carried by the shell at a point ahead of the cutter 54 for yieldingly engaging the ribs 55 of the sleeves to serve as guiding means for guiding the sleeves toward the cutter with the ribs 55 thereof in register with the ribs 56 of the shell.

An expanding clutch device as 58 is arranged in a stationary position forwardly of the cutter adapted to engage the interior of the sleeves as they come into co-operative relation with the spring fingers 57. Prior to reaching this clutch device the sleeves are

rotating freely with the shell 8 but when their interior surfaces engage the clutch device said device imparts a restraining effect tending to stop this rotation and thereby cause the spring fingers to engage in a predetermined relation against the ribs 55 of each sleeve as the sleeves move successively past them and into engagement with the ribs 56 which of course have a definite position with respect to the spring fingers.

It will be understood of course that the spring fingers are carried by the shell 8 so as to rotate therewith about the axial centre of said shell.

There may be any desired number of the spring fingers 57, but as seen in Fig. 4, three thereof is sufficient. These are arranged to project radially of the shell at spaced circumferential points. Each is slidable within a bearing 59, a spring as 60 being arranged to press it inwardly.

The shell 8 may be of any desired length but is preferably sufficiently long so as to accommodate half a dozen or more of unthreaded sleeves therein between the plunger and the cutter at all times, the length of course being gaged with respect to the length of the respective sleeves so that the combined length of the sleeves abutting together will be appropriate for correct movement of the last sleeve onto the cutter by operation of the plunger.

One important purpose of confining a plurality of sleeves within the shell is to provide for cooling said sleeves, it being intended that the space within the shell between the plunger and the cutter shall be at all times filled, or nearly so, with a suitable liquid cooling medium. For this purpose the plunger 20 is made hollow. A flexible hose as 61 is attached to the outer end of the plunger in communication with the bore 62 thereof. This hose extends into connection with one side of a pump 63. The pump may be of any desired type but is illustrated as being of the ordinary gear type, driven by a sprocket chain as 64 extending to a sprocket 65 carried by the shell 8, and from its opposite side a pipe 66 communicates with the tank H so that the oil or other cooling medium contained in said tank is continually fed upwardly by means of the pump into the interior of the shell 8 whenever the machine is operating.

The cooling medium flows through the shell 3, being of course in intimate contact with all of the sleeves therein due to the rotary movement of the shell and sleeves, and flows outwardly from the opposite end of the shell and row of sleeves as at 67, falling from said end into the open tank H.

The purpose of the packings about the shell 8 and about the plunger will now be apparent, namely, to prevent loss of the cooling liquid.

It is intended that the tank H shall be

sufficiently large so that the cooling medium will stand therein amply long to become cold before again being drawn upwardly through the pipe 66. Any means may be employed to assist the cooling of the liquid while within the tank, an instance of such means being suggested by the fan 68 mounted upon the shaft of the motor G.

In its travel through the shell 8 the cooling medium of course passes intimately not only about the shells for cooling them preparatory to being operated upon by the cutter 54 but also about the cutter itself and its supporting element 69. By thus insuring a cool condition of the sleeves preparatory to being operated upon, as well as a cool condition of the operating device or cutter it becomes possible for the cutting operation to proceed almost continuously through successive sleeves for indefinite periods. The cutter may be somewhat heated by the time it has completed the threading of each sleeve but when the next sleeve, being cool, engages it the heat will be so dissipated that an insufficient heat will be accumulated to cause any detrimental effect.

The supporting element 69 for the cutter 54, as illustrated, consists of a stiff steel bar, which may be conveniently referred to herein as the delivery bar. This bar has one end projecting into the adjacent end of the shell 8, and has the cutter mounted directly thereon in axial alignment therewith. The connection is preferably made by means of a threaded extension as 70 of the cutter engaging within a threaded socket 71 of the bar. The portion of the bar adjacent the cutter extends straight outwardly of the shell 8 and through a cylinder 72 which is spaced from the end of the shell and is formed within a standard 73 which is supported upon the bed L.

Beyond the cylinder 72 the bar 69 curves downwardly between the bed members 1 and 2 and into a second cylinder as 74 supported between said bed members, the cylinder 74 being disposed axially at right angles to the cylinder 72.

The bar 69 is of suitable size so that the sleeves after having passed over and been threaded by the cutter 54 may slide freely along the bar, and the cylinders 72 and 74 are sufficiently larger in diameter than the bar so that the sleeves may also pass freely through said cylinders, it being here noted however that the presence of one or more sleeves surrounding the bar and within each of the cylinders will serve to approximately centre the bar within the cylinders, the sleeves at this time constituting simple travelling fillers between the outer surface of the bar and the inner surface of the cylinders, and it being further noted that the right angular disposition of the two cylinders with respect to each other, together with the corresponding angular disposition of the parts of the bar therein respectively will serve as means

to prevent any appreciable displacement of the bar in all directions.

The threaded sleeves after leaving the cutter 54 may slide freely along the delivery bar, through the cylinders, and thence downwardly into the tank A where the oil and grit will be washed from the sleeves preparatory to use of the sleeves for their intended purposes.

- 10 Movement of the sleeves along the delivery bar may be produced by the forced movement of the successive sleeves passing over the cutter, but it is desirable in some cases, particularly where sleeves of the larger sizes are 15 being threaded, to provide an auxiliary propelling mechanism so as thus to relieve the sleeve which is being threaded from all unnecessary strains. An example of auxiliary mechanism for this purpose is indicated in 20 Fig. 1 of the drawings wherein it is shown to consist of a slide rod 75 mounted in a bearing 76 to slide back and forth along said bearing in a path parallel with the length of the delivery bar 69. A latch as 77 is carried at 25 one end of this rod positioned to engage the sleeves for moving them away from the cutter whenever the rod moves in that direction, but said latch being free to move in the opposite direction without corresponding movement of the sleeves. The latch is shown to be 30 gravity controlled for this purpose and to have a stop as 78 associated therewith for permitting it to swing only in a single direction as will be readily understood.
- 35 Connected with the slide rod 75 is a plunger 79 movable within a cylinder 80. A compression spring 81 is provided for urging this plunger, and with it the rod 75 in a direction toward the cutter 54, and air pressure 40 is admissible into the cylinder through a pipe 82 for moving the plunger and rod in the opposite direction.

Adjustable stops, such as those indicated at 45 83 and 84, may be provided for adjustably determining the limits of movement of the rod.

The control of air pressure through the pipe 82 may be effected by any appropriate means but in the instance illustrated is effected by the use of a pair of valves as 85 and 86, the former being an inlet valve and the latter an exhaust valve. A source of air pressure is lead to the valve 85 by means of a pipe 87, the opposite side of the valve 85 being connected with the pipe 82 so that whenever the valve 86 is open the air pressure from pipe 87 will move through pipe 82 and into the cylinder 80. The valve 86 communicates with the pipe 82 by means of a pipe 88 so that the pressure within the pipe 82 and cylinder 80 may be relieved through said valve 86 as required.

The valves 85 and 86 are positioned adjacent the shaft 25 of the clutch device for operating the plunger 20, above referred to,

and this shaft carries a pair of cams as 89 and 90 fixed thereto operable upon the valves respectively so that as said shaft rotates the valves will be opened and closed in appropriately timed relation to the delivery periods of successive sleeves from the cutter 54 so that said sleeves will be promptly picked up by the latch 77 and moved along the delivery bar a suitable distance to provide clearance for the unhindered delivery of the next succeeding sleeve from the cutter.

After the completed sleeves have moved through the cylinder 74 at the end of the delivery bar 69 they may fall permiscuously if desired into the wash tank A, but it is preferable however that they be systematically controlled during their passage through this tank, and for this purpose the drawing herewith suggests the use of an auxiliary delivery rod as 91 which is of general U-shape and which is arranged to dip downwardly into the tank, the opposite legs as 92 and 93 rounding upwardly and the whole serving as a track, in the same manner as mentioned with respect to the delivery bar 69, along which the sleeves may travel. One end of this auxiliary delivery rod, as the upper end of the leg 93 thereof, may extend into the lower end of the cylinder 74, said end being tapered to easily receive the sleeves from the lower end of the delivery bar 69, as seen in Fig. 5. The opposite end or leg as 92 may be shaped and disposed to extend to any desired location for carrying the washed sleeves as may be preferred.

The cylinder 74 is preferably made up of two longitudinal halves as 94 and 95, see Fig. 6, said halves being separable to facilitate detachment of the adjacent end of the delivery bar 69 from said cylinder whenever for any reason it is desired to remove the delivery bar from its operative position within the cylinder 72 and shell 8, as for instance when it is necessary to repair or replace the cutter 54, or the clutch member 58 carried thereby. In the instance illustrated the halves 94 and 95 are separably connected together by means of a dove-tailed slide joint between them as at 96. The half 95, which is disposed at that side of the delivery bar nearest to the standard 73, is rigidly mounted upon a cross plate 97 fastened in place between the members 1 and 2 of the bed L, and the half 94 is connected thereto, by means of the joint 96 so that it may be removed by simply lifting it upwardly away from the half 95. It is apparent from the drawings that when the half 94 is removed the delivery bar can be slid directly rearwardly out of the shell 8 and cylinder 72, but that while said half 94 is in position the delivery bar is held in its proper operative relation thereby.

Suitable means may be employed for enabling the device described to operate upon sleeves of different sizes. An example of such

means is illustrated in the accompanying drawings, and may be described as follows:

The shell 8 is made up of two tubular members as 98 and 99 telescoped snugly but re-

- 5 movably one within the other, it being intended that the bore of the inner member 99 shall be of a size calculated to properly receive sleeves to be operated upon while the outer diameter is of a size to properly fit within 10 the bore of the outer member 98. Different inner members may be provided, all having the same outside diameter, but being of varying inside diameters so that one inner member 15 may be substituted for the other as may be required to provide the proper interior size for the work in hand.

To retain the tubular members 98 and 99 assembled during operation of the machine the drawings, see Fig. 7, shows the outer member 20 as having a bayonet slot as 100 therein adapted to receive a lateral projection as 101 of the inner member.

The spring fingers 57 are carried by the inner member 99 so that the inner ends of said 25 spring fingers will at all times bear a given relation with the bore of said inner member, the ribs 56 being of course also carried by the inner member for the same purpose.

The lateral projection 101 for engaging 30 within the bayonet slot may be conveniently included as a portion of the extension 102 which projects laterally from the member 99 to provide the bearing 59 for the adjacent spring finger 57.

35 The cutter 54, and the clutch device 58, are detachable from the delivery bar through the medium of the threaded stud 70, so that these elements may be readily replaced by cutters and clutch devices of proper sizes to 40 operate upon sleeves of different sizes.

The delivery bar itself is of course removable and may be replaced by a bar of any appropriate diameter.

The cylinder 72 has a removable lining 103 45 which may be readily replaced by a lining having an interior bore of the proper size to handle the work in hand at any given time.

The cylinder 74 may be readily detached, 50 as by removal of the holding bolts 104, and replaced by a cylinder of appropriate size, and

55 Of course the delivery bar 91 may be replaceable by bars or tracks of any size or construction desired.

The magazine 18, and the parts associated therewith, may be of such size as to accommodate the largest sleeves upon which the machine is adapted to operate, and obviously sleeves of smaller sizes can be readily accommodated therein. Preferably however a separate lining member as 105 is employed having a transverse opening as 106 through its lower end to accommodate the plunger.

65 The plunger may have a removable head

as 107 so that heads of appropriate sizes may be attached, the size of this head, and of the opening 106, and of the interior of the member 99 being always made to correspond.

In making use of this machine it is simply necessary for the operator to keep a supply of unthreaded sleeves within the magazine 18. The plunger 20 will move these one at a time into the interior of the shell 8 which constitutes a cooling chamber as 108. The sleeves will cumulate and be cooled within this chamber until the chamber is filled and the first sleeve has reached the cutter 54. The movements of the plunger are timed so that pressure is at this moment being exerted against the row of sleeves in the chamber sufficient to cause the first sleeve to bite onto the cutter, whereupon slippage will begin to occur between the clutch faces 32—36 and 33—37 with the required friction to hold the sleeve from losing its grip upon the cutter. As soon as the sleeve has taken a full grip upon the cutter the relative movement of the sleeve about the cutter will automatically feed the sleeve over the cutter at a speed determined by the pitch of the cutter teeth, as will be readily understood, and meanwhile the plunger will return to allow another sleeve to fall in front of it from the magazine, the operation then being repeated. When the fully threaded sleeve has moved beyond the cutter it will be engaged by the latch 77 of the propelling mechanism and forced along the delivery bar to make room for the next succeeding sleeve as above fully explained.

The cooling liquid in moving through the shell 8 and through the row of sleeves therein will to a certain extent of course continue to flow through the sleeves while the sleeves are passing over the cutter, due to the presence of the longitudinal grooves as 109 in the cutter, and will continue through the threaded sleeve or through any number of the threaded sleeves which happen to be in close row formation on the carrier 69 immediately behind the cutter. This flow of the cooling liquid through the sleeves while the sleeves are being threaded and thereafter will carry with it the shavings or chips formed by the cutter and these will fall with the cooling liquid from the end of the threaded sleeve or sleeves, as at 110, into the tank H. The rotary movement of the threaded sleeves, and the consequent swirling action of the liquid flowing therethrough will greatly assist in the removal of shavings and chips from within the sleeves so that the sliding movement of the sleeves along the delivery bar will not be likely to be interfered with by the objectionable presence of chips between the sleeves and the delivery bar at any time during movement of the sleeves along the entire length of the delivery bar.

It is noteworthy here that the auxiliary propelling mechanism above described op-

erates to always provide the open space as 111 between adjacent threaded sleeves on the delivery bar at a point close to the cutter so as thus to facilitate the easy delivery of the cooling liquid and chips out of the end of the sleeve as indicated.

In order to further guard against frictional interference between the sleeves and the delivery bar due to the possible presence of a chip which might have eluded the cleansing action of the flowing liquid as just referred to, it is proposed that the entire length of the delivery bar may be formed with longitudinal ribs as 112 spaced apart circumferentially thereon, thus providing in effect a series of tracks for engaging the inner surface of the sleeves and a series of grooves as 113 between said tracks for accommodating such chips as may be present. The amount of frictional surface contact between the sleeves and the delivery bar is also reduced by this means.

In order that the flow of liquid through the cooling chamber 108 may be maintained at a substantially uniform maximum rate it is proposed that the pump 63 shall if desired be of sufficient capacity so that the cooling liquid will be pumped through the plunger 20 at a greater rate than its rate of delivery out of the opposite end of the cooling chamber. The level of liquid within the chamber will thus be made to rise into and overflow the magazine 18. On this account the magazine 18 is shown to be provided with an overflow opening as 114 communicating with a pan 115 exteriorally of the magazine and thence with a return pipe as 116 by which the overflowing liquid is returned into the tank H. By this means also the sleeves contained within the magazine are subjected to the cooling action of the liquid.

The entire mechanism is simply, sturdy and practical. The substantially continuous cutting action of the cutter is made possible by the means provided for the cooling of the sleeves before they are operated upon and for cooling the cutter and sleeve during the cutting operation, and by the means provided for delivering the threaded sleeves away from the cutter, any number of sleeves may be threaded in rapid succession.

As many changes could be made in this construction without departing from the scope of the invention as defined in the following claims, it is intended that all matter contained in the above description, or shown in the accompanying drawings, shall be interpreted as illustrative only and not in a limiting sense.

Having thus described my invention, what I claim as new and desire to secure by Letters Patent is:—

1. A thread cutting machine comprising a thread cutter, means providing a cooling chamber for containing a plurality of articles to be threaded, said cooling chamber ly-

ing in front of said thread cutter adapted to hold a supply of the articles preparatory to engagement of the articles with the thread cutter, and means operable to feed said articles through said chamber to the thread cutter, said chamber having an overflow opening above the level of the articles contained in said chamber, together with means to cause a flow of cooling liquid through the cooling chamber to submerge the articles therein and overflow from said chamber through said overflow opening.

2. A machine for internally threading sleeves, comprising a stationary thread cutter adapted to receive a sleeve thereover to be threaded, and means providing a cooling chamber for said thread cutter and sleeve operable to rotate the sleeve about the thread cutter to thereby thread the sleeve, together with means to cause a flow of cooling liquid through said chamber and through the sleeve during and after the threading operation, a bar upon which the cutter is mounted serving as a track along which the sleeves move after leaving the cutter, and said bar having longitudinal ribs and grooves therein to permit flow of the cooling liquid through the sleeves on the bar to thereby remove chips from within the sleeves.

3. A machine for internally threading sleeves, comprising a stationary thread cutter adapted to receive a sleeve thereover to be threaded, a tubular shell within one end of which said thread cutter is positioned, the remainder of the length of the shell extending beyond the front end of the thread cutter and being of a length to receive a row of sleeves therein, means to feed a row of sleeves along the interior of said shell to the thread cutter, means to rotate said shell, means adapted to provide interengagement between the shell and the end sleeve which is in engagement with the thread cutter whereby to rotate said end sleeve with the shell for effecting the threading operation, and means to provide a continuous flow of cooling liquid through the shell and the sleeves and about the thread cutter.

4. A machine for internally threading sleeves, comprising a tubular shell for containing a row of sleeves to be threaded, a thread cutter within one end of said shell, the remainder of the length of the shell extending beyond the front end of the thread cutter, means at the opposite end of the shell to move the row along the shell so that the sleeves will pass successively over the thread cutter, a coolant within the shell in contact with all of the sleeves therein, means to rotate the shell to thereby agitate the row of sleeves within the coolant, and means adapted to provide interengagement between the shell and the sleeve which is in engagement with the thread cutter to thereby rotate the

mentioned sleeve with respect to the thread cutter to effect the threading operation.

5. A machine for internally threading sleeves, comprising a rotatably mounted tubular shell adapted to contain a row of sleeves to be threaded, a thread cutter arranged at one end of the shell to receive sleeves thereover, the remainder of the length of the shell extending beyond the front end of the thread cutter and being of a length to receive a row of sleeves therein, means to rotate the shell, means adapted to provide interengagement between the shell and one of said sleeves to cause rotation of said sleeve with respect to the thread cutter for effecting the threading operation, a plunger to move the row of sleeves along the shell to the thread cutter, a gear mounted upon the shell to rotate therewith, driving connections between said gear and the plunger to operate the plunger from the shell, and means to cause a flow of cooling liquid through the shell for cooling the row of sleeves therein.

6. A machine for internally threading sleeves, comprising a thread cutter, a rotatably mounted tubular shell through which sleeves may be moved to the thread cutter, the thread cutter being disposed within the shell at one end thereof, the remainder of the length of the shell extending beyond the front end of the thread cutter adapted to contain a row of sleeves therein and being of smooth cylindrical interior contour, means to provide a continuous flow of cooling liquid through the shell and the sleeves and about the thread cutter, means to rotate said shell, means to move the sleeves along the shell, means carried by the shell at its end adjacent the thread cutter adapted to engage a co-operative portion provided upon an adjacent passing sleeve and cause rotation of said sleeve with the shell for effecting the threading operation, and other means to engage the passing sleeves of a character to cause a rotary movement of said sleeves with the shell for thereby insuring co-operative engagement of the sleeves with said last mentioned means.

7. A machine for internally threading sleeves, comprising a thread cutter, a rotatably mounted tubular shell through which sleeves may be moved to the thread cutter, means to rotate said shell, means to move the sleeves along the shell, means carried by the shell adapted to engage co-operative portions of the sleeves to thereby cause rotation of the sleeves with the shell for effecting the threading operation, and other means carried partly by the shell and partly by the thread cutter operable to engage the sleeves for insuring co-operative engagement of the sleeves with said last mentioned means.

8. A machine for internally threading sleeves, comprising a thread cutter, a rotatably mounted tubular shell through which

sleeves may be moved to the thread cutter, means to rotate said shell, means to move the sleeves along the shell, sleeve driving means carried by the shell adapted to engage co-operative portions of the sleeves to thereby cause rotation of the sleeves with the shell for effecting the threading operation, a sleeve clutching device carried by the thread cutter having resilient sleeve engaging portions tending to prevent rotation of the sleeves, and means carried by the shell operable to engage the sleeves to rotate them in opposition to said sleeve clutching device for thereby insuring co-operative engagement of the sleeves with said sleeve driving means.

9. A machine for internally threading sleeves, comprising a thread cutter, a delivery bar continuing from the thread cutter for receiving the threaded sleeves in telescoping relation thereover from the thread cutter, a wash tank adapted to contain a quantity of cleaning liquid, said delivery bar having a portion dipping into and out of said tank, and propelling means by which to propel the threaded sleeve along said delivery bar through said wash tank.

10. A thread cutting machine comprising a horizontally disposed tubular shell closed at one end, a threading tool partially closing the opposite end of the shell, a relatively vertically disposed chute opening into the shell adjacent the first end adapted to feed into the interior of the shell articles to be threaded, means to move the articles from adjacent the chute to the threading tool, means providing an overflow opening from the shell at a level above the top of the shell, and means to supply cooling liquid into the shell to overflow at said overflow opening.

11. A thread cutting machine comprising a horizontally disposed tubular shell closed at one end, a threading tool partially closing the opposite end of the shell, a relatively vertically disposed chute opening into the shell adjacent the first end adapted to feed into the interior of the shell articles to be threaded, means to move the articles from adjacent the chute to the threading tool, the chute having an overflow opening therein at a level above the top of the shell, and means to supply cooling liquid into the shell to overflow at said overflow opening.

12. A thread cutting machine comprising a horizontally disposed tubular shell closed at one end, a threading tool partially closing the opposite end of the shell, a relatively vertically disposed chute opening into the shell adjacent the first end adapted to feed into the interior of the shell articles to be threaded, a plunger constituting the closure at the closed end operable to move the articles from said end along the shell to the threading tool, plunger operating means, means to rotate the shell, means whereby rotation of the shell will cause an article in engagement with the

threading tool to be threaded, and means whereby the interior of the shell will be maintained full of cooling liquid to submerge the articles in said shell.

13. A thread cutting machine comprising
5 a horizontally disposed tubular shell closed at one end, a threading tool partially closing the opposite end of the shell, a relatively vertically disposed chute opening into the shell adjacent the first end adapted to feed into the interior of the shell articles to be threaded, a plunger constituting the closure at the closed end operable to move the articles from said end along the shell to the threading tool, plunger operating means, means to rotate the
15 shell, means whereby rotation of the shell will cause an article in engagement with the threading tool to be threaded, and means whereby the interior of the shell and a portion of the chute will be maintained full of
20 cooling liquid to submerge the articles in the shell and in the mentioned portion of the chute.

14. A machine for internally threading sleeves, comprising a thread cutter, a rotatably mounted tubular shell through which sleeves may be moved to the thread cutter, means to rotate said shell, means to move the sleeves along the shell, means carried by the shell adapted to engage co-operative portions of the sleeves to thereby cause rotation of the sleeves with the shell for effecting the threading operation, and means including a spring dog carried by the shell operable to engage the mentioned co-operative portions of the sleeves for insuring co-operative engagement of the sleeves with said last-mentioned means.

In testimony whereof I affix my signature.

ARCHIBALD L. WALLACE.
